UNITED STATES PATENT OFFICE

2,656,802

PRESSER DEVICE FOR SHOE SEWING MACHINES

Paul Actis, Fontaine, France

Application December 6, 1949, Serial No. 131,460
In France December 17, 1948

2 Claims. (Cl. 112—61)

1

There exist for shoe manufacturing purposes numerous types of machines for sewing lock stitches. Said machines include generally a system of aligned shafts driven into rotation by an electric motor and carrying a number of cams, e. g. four or five cams, controlling each a plurality of corresponding mechanisms incorporated to the machine.

Such cams, that are provided with as many raceways as they have parts to play, are costly and require furthermore a complete change of the cam when only one of its raceways is worn out; such changes are in fact frequent by reason of the rapid wear of certain raceways so that consequently the upkeep of the machines considered becomes extremely expensive.

Said prior machines show further numerous other drawbacks among which I may mention:

The constitution of a single-part hook which requires a substantial dismantling of the machine parts when it comes to changing a broken hook, such a breaking of the hook being a very frequent occurrence;

Similarly the constitution in a single part of the brake shoe adapted to clamp the thread, which requires, when the shoe is worn, a substantial partial dismantling of the machine for its replacement; said dismantling leads always to a loss of time, to a reduction in the efficiency of the machine and to an increase of the cost price.

My invention does away with these drawbacks and has for its object a machine for sewing shoe soles with lock stitches that require substantially no upkeep, wherein the change of the hook when broken or the change of the brake shoe when worn is performed very speedily by reason of the improved mechanical structure of said parts.

To this end, the same shaft of the improved machine carries a number of cams that corresponds substantially to the number of mechanisms forming the different components of the machine, to wit, the presser foot, the looper, the hooks, the awl and the like, said shaft being revolvably carried in bearings inside a casing filled with an oil bath.

According to a further feature of my invention, the looper is secured to the end of a telescopic arrangement, the longitudinal movements of which are produced by a cam while another cam associated with two cam followers controls its rocking movement.

According to a further feature of the invention, the brake shoe or thread clamping shoe is secured, in order to make its changing easier, to and is controlled by the end of a lever actuated through the engagement with one of the cams of a cam follower rigid with said lever and urged against the periphery of said cam by a spring provided for this purpose.

5

Similarly, the hook is constituted by two parts of which one engages a cam and controls the movement of said hook while the other is easily dismountable and forms the actual hook member.

According to a still further object of my invention, the presser foot may be raised at any moment of the operation of the machine through depression of a pedal so as to produce first the release of the presser foot and then its raising.

My invention will be better understood while its advantages and features will appear more clearly through the reading of the following description of an embodiment disclosed by way of example and by no means in a binding sense and that is illustrated in accompanying drawings, wherein:

Fig. 1 is a front elevational view of the head of said sewing machine.

Fig. 2 is a side elevational view thereof.

Fig. 3 is a longitudinal sectional view passing through the shaft axis.

Fig. 4 is a vertical sectional view of the looper.

Fig. 5 is a horizontal cross-sectional view thereof.

Figs. 6 and 7 are side elevational views of the presser foot that is shown respectively in its bolted fastening position and in its raised released position.

Fig. 8 is a side elevational view of the hook and of its control mechanism.

Fig. 9 is a plan view of the hook and

Fig. 10 is a side elevational view of the thread clamping brake.

35 The machine illustrated includes chiefly a shaft 2 (Fig. 2) revolvably carried in the ball bearings 3 housed in the flanges 4 rigid with the head of the machine, said shaft 2 being driven into rotation through the agency of a pulley 5 associated with a clutch system 6.

To the shaft are keyed eleven cams, to wit:

The cam 7 controlling the feed carriage 23

The cam 8 controlling the means for adjusting the loop at midthickness of the leather

The cam 9 controlling the presser foot 24

The cam 10 controlling the thread finger 25

The cam 12 controlling the eccentric actuating the needle 26 and awl 27

The cam 13 controlling the hook 28

The cam 14 controlling the looper 29

The cam 15 controlling the thread-stretching means 31

55 The cam 16 controlling the needle guide

The cam 17 controlling the brake shoe or thread clamping shoe 32

The cam 18 controlling the looper 29 in association with the cam 14 and a pinion 19 controlling the bobbin 33.

The head of the machine forms a fluidtight casing 21 filled with an oil bath the upper level of which may be inspected through the gate 22 and lies at a height such that the lower parts of the cams dip into said bath, whereby the rotation of the shaft 2 provides through projection a perfect lubrication of the whole mechanism; this provides, in addition to a longer life for the different parts of the machine with reference to those already on the market, a more silent operation of the machine.

The looper 29 (Figs. 1—2—4 and 5) are submitted to two different movements, to wit: a longitudinal movement in the direction of the arrow 34 (Figs. 4 and 5) and a rocking movement in the direction of the arrow 35 of Fig. 5. These displacements are obtained through the operation of the corresponding cams 18 and 14 keyed to the shaft 2 (Figs. 3, 4 and 5).

To this end, the looper 29 is secured to the end of a rod 36 the other end of which is pivotally secured to the end of a lever 37 (Fig. 5) the other end of which moves in the direction illustrated by the arrow 40 (Fig. 5) under the action of a roller 38 acting as a cam follower at the periphery of the cam 18 against which it is urged by a spring 39.

The rod 36 slides furthermore through its medial portion inside a tube 41 the front end of which pivots round a vertical axis 42 while its rear end carries two rollers 43a and 43b the axes of which are vertical and that engage respectively the opposite surfaces of the cam 14. To allow the rocking movements of the looper 29 and consequently also of the opposite end of the rod 36, the end of the lever 37 inside which is pivotally secured the rod 36 assumes the shape of a strap.

The presser foot 24 (Figs. 1, 2, 6 and 7) is pivotally secured at 44 through its rear end to a point of a vertical rod 45a the upper end of which is connected in its turn with a link member 45b pivotally connected in its turn to the front end of a lever 46 pivotally secured at 47 and the rear end of which is free. The rear surface of the vertical rod 45a is provided near its lower end with a notch 48 inside which is engaged the end of the horizontal rod 49; the latter is adapted to move longitudinally, alternatingly in the direction of the arrows 51 and 52 of Fig. 6, under the opposite actions of a spring that is not illustrated and of a lever 53 pivotally secured through one end to the abovementioned horizontal rod 49 while its other end is pivotally secured to a stationary member 54. Said lever 53 carries near its middle a roller 55 having a horizontal axis and forming a cam follower cooperating with the cam 9 keyed to the shaft 2.

To the end of the horizontal rod 49 and in alignment therewith is screwed on the other hand a further rod 56 sliding in the slideway 57 and passing through the rear well of the casing 21. The rear end of said rod forms a strap carrying two rollers 58 lying in contacting relationship with the rear surface of a vertical rod 59 passing through the said strap and the upper end of which is free while its lower end is connected with a lever 61 the displacement of which is controlled by a pedal. The rod 59 is moreover thinner at its upper end 59a than its lower end 59b, said two ends being connected through a sloping central portion 59c.

The operation of this presser foot is as follows: during the operation of the machine the presser foot is alternatingly locked and released under the action of the cam 9 cooperating with the

roller 55 engaging the periphery of the cam under the action of a spring and controlling, through the agency of the lever 53 to which it is pivotally secured, the longitudinal movement illustrated by the arrows 51 and 52 of Fig. 6 of the rod 49 the front end of which alternatingly engages and releases the notches 48 so as to clamp and release alternately the presser foot 24.

The raising of the presser foot is furthermore performed in the following manner: through action on a pedal that is not illustrated in the drawing there is obtained through the agency of a lever 61 a vertical upwardly directed displacement of the rod 59 as illustrated by the arrow 62 of Fig. 6 whereby the cam follower 53 is constrained to roll first on the thinner upper part 59a of the rod 59, then on the slope 59c thereof and lastly on the thicker lower part 59b, which produces a frictional action in the direction of the arrow 63 of Fig. 6 on the rod 56 and consequently on the lever 46 the front of which moves out of the notches 48 so as to release the presser foot 24. Through a further depression of the pedal the rod 59 continues moving in the direction of the arrow 62 of Fig. 6 while its upper end engages the rear end of the lever 46 that is urged thereby in the direction of the arrow 64 of Fig. 6 and that rocks round its pivot 47 so as to transform the movement described into a shifting in the direction of the arrow 65 of Fig. 6 of the rod 45 that is in its turn pivotally secured as disclosed to the rear end of the presser foot 24 so that this shifting of the rod 46 raises the front portion of the latter while the medial portion of the presser foot pivots round the point 44. This leads to the position of the parts illustrated in Fig. 7 and it will be readily ascertained that this raising of the presser foot may be obtained at any moment of the working of the machine through a mere depression exerted on the pedal.

Lastly it should be remarked as a further feature of the invention that the actual hook 28 and the thread clamping brake shoe 32 are each constituted by two separate associated parts. The hook 28 (Figs. 1, 2, 8 and 9) is as a matter of fact secured to the front end of a rod 66 moving in the direction of the arrow 67 of Fig. 8 under the control of a lever 68 the upper end of which is pivotally secured to said rod while its lower end is pivotally secured to a stationary member 69, said lever 68 including a horizontal pivot on which is revolubly carried a cam follower 71 engaging under the thrust exerted by the spring 72 the cam 13 keyed to the shaft 2 of the machine.

The thread clamping brake shoe 32 (Figs. 1, 2 and 10) is furthermore secured to the front end of a bell crank 73 pivotally secured at 74 and the rear end of which carries pivotally a roller 75 engaging the cam 17 keyed to the shaft 2 and against which it is urged by a spring not illustrated held between a stationary member 77 and a lateral arm 78 on the bell crank 73, the displacements in the direction of the arrow 79 of Fig. 10 of the axis of the roller 75 producing the displacement in the direction of the arrow 81 in Fig. 10 of the brake shoe 32 that engages consequently a groove in the roller 82 wherein the thread is held.

Obviously and as apparent from the preceding disclosure, my invention is by no means limited to the embodiment described and illustrated and it covers on the contrary all the modifications of the machine lying within the scope of accompanying claims.

What I claim is:

1. In a machine for sewing shoe soles with lock stitches, the combination of a single common camshaft, a presser foot, a bar adapted to lock the presser foot in its inoperative position, a cam on the camshaft, a lever controlled by said cam and adapted, when operated by said cam, to urge last mentioned bar into its inoperative position, a shaped rod of varying thickness slidingly engaging the outer end of the locking bar and registering in its inoperative position with the outer end of the locking bar through a part of reduced thickness of said shaped rod and adapted to urge said outer end of the locking bar in a direction releasing the latter with reference to the presser foot through a part of greater thickness, a pedal controlling the position of the shaped rod with reference to the locking bar, means controlling the movement of the presser bar between its operative and inoperative positions, and submitted to the action of the shaped bar when pushed by the pedal beyond the position corresponding to the release of the locking bar, a plurality of further operative components of the machine, a plurality of solid cams secured to the camshaft, cam followers operatively associated with the periphery of last mentioned solid cams and adapted to impart selectively to the different operative components the movements to be assumed thereby, springs urging the cam followers against the corresponding cams and an oil-filled casing in which the camshaft is revolvably carried with its cams extending underneath the level of the oil bath inside said casing.

2. In a machine for sewing shoe soles with lock stitches, the combination of a camshaft, a presser foot, a bar adapted to lock the presser foot in its inoperative position, a cam on the camshaft, a lever controlled by said cam and adapted, when operated by said cam, to urge the last mentioned bar into its inoperative position, a shaped rod of varying thickness slidingly engaging the outer end of the locking bar and registering in its inoperative position with the outer end of the locking bar through a part of reduced thickness of said shaped rod and adapted to urge said outer end of the locking bar in a direction releasing the latter with reference to the presser foot through a part of greater thickness, a pedal controlling the position of the shaped rod with reference to the locking bar, and means controlling the movement of the presser bar between its operative and inoperative positions, and submitted to the action of the shaped rod when pushed by the pedal beyond the position corresponding to the release of the locking bar.

PAUL ACTIS.
